(57) **CLAIM**

I claim the ornamental design for a stadium folding chair, as
shown and described.

DESCRIPTION

FIG. 1 is a perspective view of a stadium folding chair, showing my new design in an expanded configuration;
FIG. 2 is a front elevational view of FIG. 1;
FIG. 3 is a rear elevational view of FIG. 1;
FIG. 4 is a left-side elevational view of FIG. 1;
FIG. 5 is a right-side elevational view of FIG. 1;
FIG. 6 is a top plan view of FIG. 1;
FIG. 7 is a bottom plan view of FIG. 1;
FIG. 8 is a perspective view thereof, illustrated in a col-
lapsed configuration;
FIG. 9 is a front elevational view of FIG. 8;
FIG. 10 is a rear elevational view of FIG. 8;
FIG. 11 is a left-side elevational view of FIG. 8;
FIG. 12 is a right-side elevational view of FIG. 8; and
FIG. 13 is a top plan view of FIG. 8; and,
FIG. 14 is a bottom plan view of FIG. 8.
The broken lines in the figures represent stitching, and are
part of the claimed design.
